UNITED STATES PATENT OFFICE.

CARL J. E. WAKBOM, OF WESTERVILLE, OHIO, ASSIGNEE TO THE JEFFREY MANUFACTURING COMPANY, OF COLUMBUS, OHIO, A CORPORATION OF OHIO.

MINING APPARATUS.

1,267,843.

Specification of Letters Patent. Patented May 28, 1918.

Application filed October 11, 1912, Serial No. 725,323. Renewed October 27, 1917. Serial No. 198,834.

To all whom it may concern:

Be it known that I, CARL J. E. WAKBOM, a citizen of the United States, residing at Westerville, in the county of Franklin and State of Ohio, have invented a certain new and useful Improvement in Mining Apparatus, of which the following is a specification, reference being had therein to the accompanying drawings.

10 The invention relates to a mining apparatus of the class in which each machine is supported on a movable base (preferably a wheeled truck) and carries a horizontally projecting kerf cutting mechanism which is capable of movement horizontally and is adapted to operate while supported on the base or truck. In using a mining apparatus of this type it is customary to lay a single track along the center of the room or entry being cut. The mining mechanism or apparatus is then moved forward along this track to a point near the face and use is made of the cutting mechanism thereof to cut a kerf extending across the face from one side of the room to the other. The cutting mechanism remains supported on the truck while the cutting is being carried on.

In another application, Serial No. 725,323 filed October 11, 1912, I have shown an apparatus in which the cutting mechanism is movable not only transversely across the front of the machine (preferably angularly about a fixed vertical axis), but also translatively outward and inward away from and toward the central parts of the truck; power operated means are provided for moving the cutting mechanism horizontally (in this case radially) relatively to the frame to feed the mechanism to its work; the cutter frame is held in a definite angular relation to the base frame for each position of transverse adjustment; and the outer limit of radial movement is controllable and can be varied for different angular positions. The construction is such that the machine can be used to cut kerfs having outlines other than semi-circular. By my present invention I have provided an apparatus in which the cutting mechanism is movable not only transversely and translatively, as aforesaid, but is also adjustable vertically.

As is well known it is customary in the mining of coal to cut a kerf under the wall to be removed and then to break down the material above the kerf. But under some

conditions it is possible and in fact preferable to cut the kerf not at the bottom but at a plane considerably above the bottom. An apparatus embodying my invention is adapted for use under those conditions which make possible the cutting of an elevated kerf. The desirability of a kerf some distance above the mine floor frequently arises from the presence in the coal of what is known as a "dirty band," this usually being composed of slate or other refuse material which it is undesirable to permit to become mixed with the coal. In places where such a "dirty band" is met with it is desirable to cut it away. This cutting away of the "dirty band" not only removes it and prevents it from becoming mixed with the coal, but also provides the necessary kerf. As the "dirty band" is at different heights in different mines or even in different parts of the same mine, it is desirable that any apparatus designed for cutting it out be provided with means whereby vertical adjustment can be effected. An apparatus embodying my invention is especially adapted for the class of work to which I have referred. It can be readily adjusted vertically, or angularly, and it can easily be transported from place to place.

I have shown an apparatus which comprises a mining machine of the breast type vertically adjustably supported on a turntable which is mounted on a wheeled truck. But it will be understood that there can be wide variation as concerns the specific form of cutting mechanism used and as concerns the means for driving and controlling it.

In the apparatus shown, the cutting mechanism is supported at a relatively high elevation, as this is usually desirable in "dirty band" work. As shown, the cutting mechanism is so supported as to have a relatively high limit of adjustment downward. But it will be understood that the invention is not limited as concerns the limits of the range of adjustment.

The principal object of the invention is to provide a mining machine of the type specified having a cutting mechanism which is movable horizontally both angularly and translatively, which is adjustable vertically and which preferably is adapted for the cutting of kerfs non-circular in outline.

Another object is to provide an apparatus by means of which a series of cuts can be

made at a variety of elevations radially from a center. A further object is to provide means for effecting and controlling the movement of the bed frame or mining machine support with respect to the main truck frame. Still further objects will be apparent from the following specification and claims.

Of the accompanying drawings which illustrate the embodiment of my invention which I deem preferable,

Figure 1 is a side elevation of the apparatus as a whole;

Fig. 2 is a longitudinal sectional view; Fig. 3 is a view taken looking upward at the mining machine and mining machine supporting devices separated from the truck;

Fig. 4 is a plan view of the truck with the mining machine and the mining machine supporting devices removed;

Fig. 5 is a diagrammatic view indicating one way in which an apparatus embodying my invention may be used.

Referring to the drawing, 1 represents as a whole the main frame of the truck which is preferably a single metallic plate 2 reinforced at its edges by means of angle irons 3, 3, and 4, 4. Stiffening angles 5, 5, are preferably also provided near the center. By means of suitable bearing brackets 6, 6, the frame 1 is mounted upon axles 7, 7 to which are secured track wheels 8, 8. The axles and track wheels are not symmetrically disposed with respect to the transverse central plane of the truck but are considerably nearer one end than the other.

For purposes of illustration, I have shown on the truck a breast mining machine of standard construction. The machine shown is similar to that described in the patent to H. B. Dierdorff No. 684,356. The machine as a whole is indicated by 21, and it is shown inverted, that is with the parts which are usually considered the bottom parts uppermost.

The mining machine comprises a carriage or cutter frame 23 and mounted upon this cutter frame is a cutting mechanism in the form of an endless cutter chain 24 provided with cutters 25. The connections between the cutter frame 23 and the main truck frame 1 are such that the cutter frame is vertically adjustable and is also movable horizontally either angularly or bodily outward and inward. When the cutter frame is a part of a standard breast mining machine such as is here shown it is mounted on a bed frame 22 in such a way that it is longitudinally movable with respect thereto. The side parts of the bed frame constitute a guide which permits the cutter frame to have translative horizontal movements but prevents relative angular movements with respect to the bed frame 22.

In the construction shown, the bed frame 22 is carried by a supporting frame which is movable horizontally with respect to the base frame. Preferably this movement of the supporting frame takes place about the fixed vertical axis of a suitable pivot device. It will be observed that this pivot device together with the aforesaid guide on the bed frame 22 insure that the cutter frame, whenever a particular point thereof occupies any given position in relation to the base frame, shall bear a corresponding and invariable angular relation to the base frame. In other words, by virtue of this construction, the cutter frame is held against indefinite movements, its angular relation to the base frame being definitely fixed for each position of its transverse adjustment.

Midway between the sides of the truck frame 1 and midway between the axles 7, 7, there is provided a bracket 9 which is fitted into a suitable opening in the plate 2 and is provided with a vertical bearing aperture 10. Located at equal distances from the center of the aperture 10 and preferably equally spaced circumferentially are a number of bearing rollers 11, 11 each arranged with its axis extending radially through the center line of the central aperture. The number of these bearing rollers is not essential but in the drawings I have shown six. As shown, four of these rollers are mounted on the brackets 6, 6, in which the axles are journaled. The other two rollers are mounted in special brackets 12, 12 secured to the plate 1. Each of the rollers is positioned in an aperture in the plate 1 in the upper edge of the roller somewhat above the top plane of the plate.

13 is a spider having an outer ring 14 fitted to rest upon the rollers 11, 11 and spokes 15, 15, connecting with a central hub 16 in which is mounted a pivot pin 17 fitting into and engaging the aperture 10 in the bracket 9.

Secured to the ring 14 at opposite sides thereof are arcuate base plates 18, 18 which are provided at their opposite ends with vertical apertures in which are mounted upright studs or supporting devices 19, 19, which are arranged so as to define a polygon, preferably a rectangle. Each of the four studs 19, 19 is provided at its outer side with a vertical groove in which there is mounted a rack 20. The spider 13, base plate 18 and uprights 19 constitute the supporting frame previously referred to.

Suitable devices are provided for connecting the bed frame 22 of the mining machine with the said upright studs or supports 19, 19. As shown, there are two brackets 39, 39, which are bolted or riveted to the bed frame. Each of these brackets is provided at each end with an arm 40, which has at its outer end a vertical aperture 41 adapted to re-

ceive one of the upright studs 19. The studs, by their engagement with the walls of the apertures of the bracket arms, serve to guide the mining machine for vertical movement.

In order to control the vertical movement of the mining machine there is mounted in suitable bearings in the arms 40 of each bracket 39 a longitudinal shaft 42 which carries at each end a pinion 43 adapted to mesh with the rack 20 in the adjacent stud 19. Mounted upon each shaft 42 is a worm wheel 44 with which meshes a worm 45 on a short transverse shaft 46. Each shaft 46 is mounted in suitable bearings on one of the arms 40. Mounted upon each shaft 46 is a hand lever 47, and this lever is connected with the shaft by means of a ratchet and pawl mechanism 48. It will be seen that by simultaneously turning the two shafts 46 at opposite sides of the machine by means of the hand levers 47, 47, the longitudinal shafts 42, 42, can be rotated and the mining machine can be raised or lowered through the engagement of the pinions 43, 43, with the racks 20, 20. The worm and wheel connections at 44, 45, 44, 45, serve to lock the machine in whatever position of adjustment it may be left.

Preferably in order that the two shafts 42, 42, may be operated together without the possibility of one side of the machine being lifted higher than the other, I provide a power connection between the two shafts.

This power connection comprises two vertical shafts 49, 49 on opposite sides of the mining machine. Each shaft is supported near its upper end by a bracket 50 secured to the mining machine frame, and at its lower end by a bracket 51 having bearings on the corresponding shaft 42. Each shaft 49 is connected at its lower end with the corresponding shaft 42 by means of bevel gears 52, and each shaft carries at its upper end a sprocket wheel 53. An endless chain 54 passes over the two sprocket wheels.

At its rear end the cutter chain 24 runs over a sprocket wheel 26 on the cutter frame and at its forward end passes over suitable guides and idler sprocket wheels. Mounted upon the carriage or cutter frame 23 at the rear end is a motor 27 which is connected by means of suitable gearings 28, 29, with the sprocket wheel 26. By means of this gearing the cutter chain can be driven and when the carriage is moved forward will cut a kerf into the coal face. The mechanism for feeding the carriage forward is shown in Figs. 2 and 3. This comprises two racks 30 secured to the main frame at opposite sides and a transverse feed shaft 31 which is provided at opposite ends with pinions 32, 32, which mesh with the racks. Loosely mounted upon the shaft 31 are two worm wheels 33, 33^a with which mesh worms 34 and 35 on longitudinal shafts which are connected

at their forward ends by means of gearing 36 and 37 with the motor 27. By means of the gearing 36 and 37 the shafts are driven in opposite directions at different speeds. Either of the worms 33 or 33^a can be connected with the shaft 31 by means of the clutch 38. When the connection is such that power is transmitted through the gearing 36 and the worm 34 the carriage or motor frame will be fed slowly forward. When the connection is such that power is transmitted through the gearing 37 and the worm 35, the carriage will be retracted relatively rapidly.

When the invention is embodied in an apparatus of the form shown in the drawings, I prefer to follow the method of operation which is indicated in Fig. 5. A track 55 is laid down the center of the room and the machine is run into the room on this track. When the machine has reached the proper place, the truck wheels are blocked and the machine is swung around to one side as shown in full lines in Fig. 5. Then by means of the hand levers 47 and the gearing which has been described the machine can be moved vertically to bring the cutter mechanism to the height at which it is desired to cut the kerf. The two sides of the machine are maintained at the same height by means of the power connection between the lifting device at the opposite sides. After the machine has been properly adjusted as to height, it is locked in place by means of suitable jacks. Then the cutter mechanism is started and by means of the feed device which has been described, the carriage or cutter frame is advanced and a kerf is cut in the face of the coal. After the first kerf is cut the cutter or the carriage frame is retracted, the jacks are loosened and the machine is swung to the position indicated by dotted lines in Fig. 5. The machine is secured in this second position, and a second cut is then made as before. This operation is repeated, the mining machine being swung on the turntable until a complete kerf semicircular in outline has been cut into the coal. Then the machine is removed from the room and the coal is broken down in the usual way. It will be noted that by the use of this apparatus in the way above described, the room has a semi-cylindrical face instead of a plane face. This, however, is not a disadvantage, but on the contrary is a distinct advantage as loading of the coal is made easier.

It will be understood that the apparatus can be used in ways differing from the way above described and is not limited to the cutting of a complete semi-circular series of radial cuts. As the cutting mechanism is movable radially away from and toward the central parts of the truck, and as the outer limit of cutting is readily controllable for

each angular position by means of the lever 38 the radial distances from the central part of the truck to the outer edge of the kerf at different points, circumferentially separated, can be varied as may be desired to cut a kerf having an outline other than a simple semi-circular outline, such as that indicated in Fig. 5. In this respect an apparatus embodying my invention has marked advantage over earlier mechanisms which were adapted only for cutting arcuate kerfs.

What I claim is:—

1. In a mining apparatus, the combination of a main base frame, a bed frame, connections between the two frames providing for movement of the bed frame vertically with respect to the base frame and angularly with respect thereto about a vertical axis, a horizontally extending cutter frame, connections between the cutter frame and the bed frame adapted to permit longitudinal movement of the former away from and toward the said axis and, in coöperation with the connections between the base frame and bed frame, to support the cutter frame in an unvarying definite angular relation to the base frame for each position of angular adjustment in which the said bed frame is held, cutting mechanism carried by the cutter frame at the outer end thereof and movable at right angles to the lines of movement of the said cutter frame, and power feed devices coöperating with the cutter frame to advance the said cutting mechanism toward the coal beyond all other parts of the machine, whereby a broad kerf can be cut with the bed frame in any position with respect to the base frame.

2. In a mining apparatus, the combination of a main base frame, a bed frame, connections between the two frames providing for movement of the bed frame vertically with respect to the base frame and angularly with respect thereto about a vertical axis, a horizontally extending cutter frame, connections between the cutter frame and the bed frame adapted to permit longitudinal movement of the former away from and toward the said axis and, in coöperation with the connections between the base frame and bed frame, to support the cutter frame in a definite unvarying angular relation to the base frame for each position of angular adjustment in which the said bed frame is held, continuously moving constantly acting cutting mechanism carried by the cutter frame at the outer end thereof, and power feed devices coöperating with the cutter frame to advance the said cutting mechanism toward the coal beyond all other parts of the machine, whereby a kerf can be cut with the bed frame in any position with respect to the base frame.

3. In a mining apparatus, the combination of a main base frame, a bed frame connec-

tions between the two frames providing for movement of the bed frame vertically with respect to the base frame and angularly with respect thereto about a vertical axis, a horizontally extending cutter frame, connections between the cutter frame and the bed frame adapted to permit longitudinal movement of the former away from and toward the said axis and, in coöperation with the connections between the base frame and bed frame, to support the cutter frame in a definite unvarying angular relation to the base frame for each position of angular adjustment in which the said bed frame is held, cutting mechanism carried by the cutter frame at the outer end thereof and active at points widely separated transversely of the cutter frame, and power feed devices coöperating with the cutter frame to advance the said cutting mechanism toward the coal beyond all other parts of the machine, whereby a broad kerf can be cut with the bed frame in any position with respect to the base frame.

4. In a mining apparatus, the combination of a main base frame, a supporting frame mounted on the base frame and movable with respect thereto about a vertical axis, a bed frame mounted on the supporting frame for rotary movement therewith and vertically adjustable with respect thereto, a cutter frame mounted on the bed frame for movement away from and toward the said axis, cutting mechanism carried by the cutter frame at the outer end thereof and active at points widely separated transversely of the cutter frame, and power feed devices coöperating with the cutter frame to advance the said cutting mechanism toward the coal beyond all other parts of the machine, whereby a broad kerf can be cut with the bed frame in any position with respect to the base frame.

5. In a mining apparatus, the combination of a wheeled truck, a bed frame, connections between the two frames providing for movement of the bed frame vertically with respect to the base frame and angularly with respect thereto about a vertical axis, a horizontally extending cutter frame, connections between the cutter frame and the bed frame adapted to permit longitudinal movement of the former away from and toward the said axis and, in coöperation with the connections between the base frame and bed frame, to hold the cutter frame in a definite angular relation to the base frame for each position of angular adjustment in which the said bed frame is held, cutting mechanism carried by the cutter frame at the outer end thereof and active at points widely separated transversely of the cutter frame, and power feed devices coöperating with the cutter frame to advance the said cutting mechanism toward the coal beyond all other parts of the machine.

of the machine, whereby a broad kerf can be cut with the bed frame in any position with respect to the base frame.

6. In a mining apparatus, the combination 5 of a main base frame, supporting track wheels therefor, an elongated horizontally extending movable cutter frame, connections between the cutter frame and the base frame adapted to permit horizontal movement of 10 the cutter frame only endwise outward and inward in relation to the base frame and laterally across the front of the base frame from points outside the vertical plane of one track rail to points outside the vertical plane 15 of the other track rail, said connections being adapted also to permit vertical movement of the cutter frame and to insure that the cutter frame, whenever a particular point thereof occupies any given position in relation to 15 the base frame, shall bear a corresponding and invariable angular relation to the base frame, a kerf cutting mechanism carried by the cutter frame and comprising devices constantly moving relatively thereto, means for 20 adjusting the cutter frame vertically relatively to the base frame, and means supported entirely on the base frame for moving the cutter frame horizontally relatively to the base frame while the cutting mechanism 25 is in operation to advance the latter beyond all other parts of the machine.

7. In a mining apparatus, the combination of a main base frame, supporting track wheels therefor, a horizontally extending cutter frame, connections between the two frames adapted to permit lateral and vertical movement of the cutter frame and to insure that the cutter frame, whenever a particular point thereof occupies any given position in relation to 30 the base frame, shall bear a corresponding and invariable angular relation to the base frame, said connections comprising a horizontal guide and a vertical pivot respectively permitting translative 35 movements outward and inward and angular movements from points outside the vertical plane of one track rail to points outside the vertical plane of the other track rail, a kerf cutting mechanism carried by the cutter frame and comprising devices constantly moving relatively thereto, means for 40 adjusting the cutter frame vertically relatively to the base frame, and means for moving the cutter frame relatively to the base 45 frame while the cutting mechanism is in operation to advance the latter beyond all other parts of the machine.

8. In a mining apparatus, the combination of a main base frame, supporting track 50 wheels therefor, a horizontally extending cutter frame, connections between the cutter frame and the base frame adapted to permit horizontal movement of the cutter frame bodily outward and inward and laterally across the front of the base frame from points outside the vertical plane of one track rail to points outside the vertical plane of the other track rail, said connections being 55 adapted also to permit vertical movement of the cutter frame and to insure that the cutter frame, whenever a particular point thereof occupies any given position in relation to the base frame, shall bear a corresponding and invariable angular relation to the base 60 frame.

horizontal movement of the cutter frame bodily outward and inward and laterally across the front of the base frame from points outside the vertical plane of one track rail to points outside the vertical plane of the other track rail, said connections being adapted also to permit vertical movement of the cutter frame and to insure that the cutter frame, whenever a particular point thereof occupies any given position in relation to the base frame, shall bear a corresponding and invariable angular relation to the base frame, a kerf cutting mechanism carried by the cutter frame and comprising devices constantly moving relatively thereto, means for 70 adjusting the cutter frame vertically relatively to the base frame, and means supported entirely on the base frame for moving the cutter frame horizontally relatively to the base frame while the cutting mechanism 75 is in operation to advance the latter beyond all other parts of the machine.

9. In a mining apparatus, the combination of a main base frame, supporting track wheels therefor, a horizontally extending cutter frame, connections between the two frames adapted to permit lateral and vertical movement of the cutter frame and to insure that the cutter frame, whenever a particular point thereof occupies any given position in relation to the base frame, shall bear a corresponding and invariable angular relation to the base frame, said connections comprising a horizontal guide and a vertical pivot respectively permitting translative 90 movements outward and inward and angular movements from points outside the vertical plane of one track rail to points outside the vertical plane of the other track rail, a kerf cutting mechanism carried by the cutter frame and comprising devices constantly moving relatively thereto, means for 95 adjusting the cutter frame vertically relatively to the base frame, and means for moving the cutter frame relatively to the base 100 frame while the cutting mechanism is in operation to advance the latter beyond all other parts of the machine.

10. In a mining apparatus, the combination of a main base frame, supporting track 115 wheels therefor, a horizontally extending rigid cutter frame, connections between the cutter frame and the base frame adapted to permit horizontal movement of the cutter frame bodily outward and inward and laterally across the front of the base frame from points outside the vertical plane of one track rail to points outside the vertical plane of the other track rail, said connections being 120 adapted also to permit vertical movement of the cutter frame and to insure that the cutter frame, whenever a particular point thereof occupies any given position in relation to the base frame, shall bear a corresponding and invariable angular relation to the base 125 frame.

8. In a mining apparatus, the combination of a main base frame, supporting track wheels therefor, a horizontally extending cutter frame, connections between the cutter frame and the base frame adapted to permit 130

- frame, a kerf cutting mechanism carried by the cutter frame and comprising cutting devices constantly moving relatively thereto, a driving motor for the cutting mechanism fixedly connected to the cutter frame, means for moving the cutter frame relatively to the base frame while the cutting mechanism is in operation to advance the latter beyond all other parts of the machine and cause the cutting of a kerf variable in depth when measured radially from the central part of the truck, and means for adjusting the cutter frame vertically relatively to the base frame to vary the height of the kerf.
11. In a mining apparatus, the combination of a main base frame, supporting track wheels therefor, a horizontally extending cutter frame, connections between the cutter frame and the base frame adapted to permit horizontal movement of the cutter frame bodily outward and inward and laterally across the front of the base frame from points outside the vertical plane of one track rail to points outside the vertical plane of the other track rail, said connections being adapted also to permit vertical movement of the cutter frame and to insure that the cutter frame, whenever a particular point thereof occupies any given position in relation to the base frame, shall bear a corresponding and invariable angular relation to the base frame, a kerf cutting mechanism carried by the cutter frame and comprising devices constantly moving relatively thereto, means for adjusting the cutter frame vertically, and means carried entirely by the base frame for moving the cutter frame horizontally relatively to the base frame while the cutting mechanism is in operation to advance the latter beyond all other parts of the machine.
12. In a mining apparatus, the combination of a main base frame, supporting track wheels therefor, a horizontally extending rigid cutter frame, connections between the two frames adapted to permit vertical adjustment of the cutter frame and comprising a vertical pivot and a horizontal guide respectively permitting angular movements of the cutter frame around said pivot and translative movements of the cutter frame relative to said pivot, a motor fixedly connected to the cutter frame to move therewith, a kerf cutting mechanism carried by the cutter frame and driven by the motor, the said mechanism comprising devices constantly moving relatively to the cutter frame, power feed devices coöperating with the cutter frame to advance the said cutting mechanism toward the coal beyond all other parts of the machine, and means for adjusting the cutter frame vertically relatively to the base frame to vary the height of the kerf.
13. In a mining apparatus, the combination of a movable main base frame, a horizontally projecting rigid cutter frame carried by the base frame and movable with respect thereto angularly about a vertical axis fixed in relation to the base frame and radially outward and inward toward and from the coal being cut, a motor fixedly connected to the cutter frame to move therewith, a kerf cutting mechanism carried by the cutter frame and driven by the motor, the said mechanism comprising devices constantly moving relatively to the cutter frame, power feed devices coöperating with the cutter frame to advance the said cutting mechanism toward the coal beyond all other parts of the machine, and means for adjusting the cutter frame vertically relatively to the base frame to vary the height of the kerf.
14. In a wheel supported mining apparatus adapted to be transported over the tracks of a mine and to cut a horizontal kerf extending across its front while supported on a track extending longitudinally toward the face of the coal, the combination of a base frame, supporting track wheels therefor, an elongated horizontally extending cutter frame, an endless cutter chain mounted to move in a horizontal path around the periphery of the cutter frame, said cutter frame and chain having their rear parts arranged permanently directly above the base frame, supporting connections between the cutter frame and the base frame adapted to permit the cutter frame and chain to move bodily vertically and longitudinally and to turn around an upright axis within the vertical bounding lines of the base frame so that the front part of the cutter frame and chain are moved laterally across the longitudinal lines of the base frame, said supporting connections comprising a supporting frame mounted to swing laterally in relation to the base frame, and having a plurality of upright supports arranged at the angles of a widely extended horizontal polygon, two of said upright supports being disposed laterally opposite each other in front of the others and the cutter frame being disposed between said front supports to extend forward across their vertical transverse plane to points in front of the base frame, motor devices carried by the base frame, and means actuated by the motor devices for driving the cutter chain and simultaneously moving the cutter frame and chain horizontally to cut the kerf.
15. In a wheel supported mining apparatus adapted to be transported over the tracks of a mine and to cut a horizontal kerf extending across its front while supported on a track extending longitudinally toward the face of the coal, the combination of a base frame, supporting track wheels therefor, an elongated horizontally extending cut-

ter frame, an endless cutter chain mounted to move in a horizontal path around the periphery of the cutter frame, said cutter frame and chain having their rear parts arranged permanently directly above the base frame, supporting connections between the cutter frame and the base frame adapted to permit the cutter frame and chain to move bodily vertically and longitudinally and to turn around an upright axis within the vertical bounding lines of the base frame so that the front part of the cutter frame and chain are moved laterally across the longitudinal lines of the base frame, said supporting connections comprising a supporting frame mounted to swing laterally in relation to the base frame and having four upright supports arranged at the angles of a widely extended horizontal quadrangle, two of said supports being disposed laterally opposite each other in front of the others and the cutter frame being disposed between said front supports to extend forward across their vertical transverse plane to points in front of the base frame, means for adjusting the cutter frame upwardly and downwardly relative to the upright supports, motor devices carried by the base frame, and means actuated by the motor devices for driving the cutter chain and simultaneously moving the cutter frame and chain horizontally to cut the kerf.

16. In a wheel supported mining apparatus adapted to be transported over the tracks of a mine and to cut a horizontal kerf extending across its front while supported on a track extending longitudinally toward the face of the coal, the combination of a base frame, supporting track wheels therefor, an elongated horizontally extending rigid cutter frame, an endless cutter chain mounted to move in a horizontal path around the periphery of the cutter frame, said cutter frame and chain having their rear parts arranged permanently directly above the base frame, supporting connections between the cutter frame and the base frame adapted to permit the cutter frame and chain to move bodily vertically and longitudinally and to turn around an upright axis within the vertical bounding lines of the base frame so that the front part of the cutter frame and chain are moved laterally across the longitudinal lines of the base frame, motor devices carried by the base frame, and means actuated by the power of the motor devices for driving the cutter chain and simultaneously moving the cutter frame and chain horizontally to cut the kerf.

17. The combination of a wheel supported truck, a frame arranged to oscillate horizontally thereon and comprising four upwardly extending vertical columns arranged at the angles of a widely extended horizontal rectangle directly above the truck, guides

vertically adjustable on said columns, a frame carrying the said guides, a horizontally extending endless chain cutting apparatus supported on the last said frame and bodily movable forward relatively to the truck to points in advance of all other parts of the machine and bodily movable transversely relatively to the truck and vertically adjustable with the said vertically adjustable guides, and means for simultaneously adjusting the guides to move the cutting apparatus vertically in parallelism.

18. The combination of a frame, a horizontally extending endless chain cutting apparatus mounted to move bodily longitudinally in the said frame, guides connected to the sides of the frame, two relatively near its forward end and two relatively near its rear end, vertically elongated guide elements with which said guides respectively engage, means for simultaneously adjusting the guides to move the cutting apparatus vertically in parallelism, a bottom support for the vertical guides connected thereto, and a wheel supported truck directly below the bottom support and connected thereto to permit the forward part and the rear part of the said bottom support to move transversely to the longitudinal planes of the truck, the said cutting apparatus being mounted to project to points in advance of all other parts of the machine.

19. In a wheel supported mining apparatus adapted to be transported over the tracks of a mine and to cut a horizontal kerf extending across its front while supported on a track extending longitudinally toward the face of the coal, the combination of a base frame, supporting track wheels therefor, an elongated horizontally extending cutter frame, an endless cutter chain mounted to move in a horizontal path around the periphery of the cutter frame, supporting and guiding connections between the cutter frame and the base frame comprising a supporting frame mounted directly above the base frame to swing laterally in relation to the base frame, and having four upright supports arranged at the angles of a widely extended horizontal quadrangle, the cutter frame and chain being disposed between the upright supports to extend forward across the transverse plane of the front pair of said supports to points in front of the base frame, and means for movably supporting the cutter frame on the said upright supports to permit the cutter frame and chain to move bodily forward and backward, a driving motor fixed in relation to the cutter frame, and means driven by the motor for moving the cutter frame and chain and the motor bodily relatively to the base frame to cut the kerf.

20. In a wheel supported mining apparatus adapted to be transported over the

tracks of a mine and to cut a horizontal kerf extending across its front while supported on a track extending longitudinally toward the face of the coal, the combination of a 5 base frame, supporting track wheels therefor, a supporting frame mounted on the base frame directly over its wheel base to turn in horizontal planes and comprising a plurality of upright supports disposed at 10 the angles of a widely extended horizontal polygon, a horizontally disposed bed frame vertically adjustably mounted on the upright supports, a horizontally extending cutter frame mounted for longitudinal movement on the bed frame, an endless cutter chain mounted to move in a horizontal path 15

around the periphery of the cutter frame, and a motor for driving the cutter chain fixedly connected to the cutter frame, the cutter frame and chain being disposed near 20 the upperside of the bed frame and the motor being disposed in planes below the cutter chain in position to move with the cutter frame in the space between the axes of the said upright supports. 25

In testimony whereof I affix my signature in presence of two witnesses.

CARL J. E. WAXBOM.
